Primary Examiner—Susan J. Lucas

[57] CLAIM

The ornamental design for a combined conductivity monitor and controller, as shown.

DESCRIPTION

FIG. 1 is a perspective view of a combined conductivity monitor and controller embodying my design;

FIG. 2 is a front view thereof;

FIG. 3 is a side view thereof;

FIG. 4 is a rear view thereof;

FIG. 5 is a top view thereof; and

FIG. 6 is a bottom view thereof.

FIG. 1

FIG. 5

FIG. 2

FIG. 3

FIG. 4

FIG. 6
